PRESSING MACHINE

Albert Matthews, Cincinnati, Ohio, assignor to
The American Laundry Machinery Company,
Norwood, Ohio, a corporation of Ohio

Application August 6, 1934, Serial No. 738,597

5 Claims. (Cl. 38—25)

This invention relates to a pressing machine of the type used in laundry and garment work.

An object of the invention is to provide in a press having a pair of cooperating elements relatively movable into and out of pressing relation, means for closing the press and a positive mechanical latch for holding the press closed before final pressure is applied.

Another object of the invention is to provide a press having coacting pressing members, one of which has a cover distensible by inflation, together with means for closing the press, means for locking the pressing members in safe closed position, and novel means for thereafter automatically inflating the distensible cover.

Another object of the invention is to provide a novel pressing element of the type having a cover distensible by inflation and comprising means for preventing deterioration of the side portions of said cover when in constant use.

Other objects of the invention are the provision of suitable mechanism and control means for carrying out the above described objects, as will appear from the accompanying specification taken with the drawings and the essential features of which will be summarized in the claims.

In the drawings, Fig. 1 is a side elevation partly in section of a press embodying my invention with the press parts in open position and with the control mechanism shown in diagrammatic form; Fig. 2 is a view similar to Fig. 1 showing the press closed for a pressing operation; Fig. 3 is an enlarged sectional view of the buck and chest in pressing position; while Fig. 4 is a plan view on a slightly diminished scale of the buck illustrated herewith.

I have illustrated my invention as applied to a press of the scissors type having a frame 10 upon an upstanding bracket of which is pivotally supported a head lever 11 carrying a chest 12 at its forward end and having a spring 13 connected between the rearward end and the frame so that the chest is normally biased to press open position. A buck 14 is mounted on the frame 10 in position to coact with the chest.

The means for closing the press against the bias of spring 13 comprises an operating lever 15 pivotally mounted in the frame 10 at 16 and having motion transmitting mechanism connecting it with the head lever 11 so that movement of operating lever 15 in a clockwise direction about its pivot will move the head 12 into operative position adjacent or contacting buck 14. The motion transmitting mechanism illustrated herewith comprises a link 17 pivotally connected with

the operating lever at one end and at its other end pivotally connected with an oscillating lever 18 which is pivotally supported at 19 on the frame. The other end of lever 18 is pivotally connected with a member 20 so that lever 18 and member 20 comprise a toggle. This toggle in turn is connected at 21 with the knuckle of another toggle mechanism comprising members 22 and 23 pivotally connected to the head lever and to the frame respectively. It will be apparent therefore that downward movement of the operating lever will move the double toggle mechanism toward straightened position, as shown in Fig. 2, so as to close the press. Preferably, this toggle mechanism will not move quite to the locked position so that upon the release of the operating lever 15 spring 13 is operative to open the press.

Various means might be utilized for closing the press. For instance, it might be closed by operator operated means but preferably is provided with power means. That illustrated herewith comprises a cylinder and piston motor 24 which includes a cylinder 25 pivotally supported from a bracket on the frame and equipped with a suitable piston 26, whose piston rod 27 is pivotally connected at 28 to the forward end of the operating lever.

The means for controlling the flow and exhaust of pressure fluid to motor 24 is illustrated as comprising a pair of valve casings 29 and 30 in series for admitting pressure fluid from a source of supply 31 through conduit 32, valve casing 29, conduit 33, valve casing 30 and conduit 34 to the motor. Each of the valve casings incloses a combined inlet and exhaust valve and since the constructions are similar one only will be described. For instance, in valve casing 29 the inlet valve 29a and the exhaust valve 29b are mounted on a common stem 29c which is spring pressed to the position shown in the drawings so as to maintain the inlet valve normally closed and the exhaust valve normally open. The valve is manipulated by means of a manual 29d. Exhaust from the valve casing is provided through an open port 29e.

For holding the press closed before final pressure is applied to the pressing members, a positive mechanical latch is provided acting on some portion of the motion transmitting mechanism between the closing means and the head lever. The form illustrated herewith comprises an L-shaped latch 35 pivotally supported at 36 in the frame and having in its upwardly extending arm a notch 37 adapted to receive a pin 38 carried by the operating lever. The latch is biased in pin-

engaging direction by a spring 39. The means provided for releasing the latch comprise a foot treadle 40 pivoted at 41 to the frame with its free end in position to engage the forwardly extending arm of the latch 35.

While certain features of my invention may be utilized in presses having pressing elements differing from those illustrated, I prefer to use a buck as shown of the type having a cover distensible by inflation for producing final pressure after the press is closed. This type of press has certain advantages, among them being the fact that the inflated bed provides a perfect accommodation for inequalities in the articles worked upon and, furthermore, the pressure may be applied equally over the entire pressing surface thus giving a greatly increased and uniform pressing or ironing effect.

The buck illustrated herewith comprises a base member 42 which is secured to the frame and comprises a work supporting portion 43 and side portions 44. Over this base member in loose fitting relation extends a cover 45 which continues down along the side portions 44 and is folded beneath the base member at 46 where the free edges of the cover are secured to the base member in fluid-tight relation. A novel securing means is illustrated comprising an L-shaped flange 47, one arm of which is secured by bolts 48 to the base member in a manner to clamp the cover to the base. The upwardly extending arm 49 of the flange extends upwardly outside the cover in a manner to support it along the side portions of the base member and extends substantially to the plane of the working portion of the base member. In other words, with reference to Figs. 2 and 3, the arm 49 of the flange supports the buck cover almost to the point of contacting with the chest 12 when the pressing members are in their pressing position. The cover is substantially impervious to the fluid used and is both flexible and slightly distensible, one suitable form comprising alternate layers of rubber and fabric. Due to the alternate inflation and deflation of this cover, flexing takes place where the cover changes direction between the work supporting portion and the side portions of the buck and it is the purpose of the flange member 47 to support the cover at this point and prevent undue flexing. The supply of pressure fluid for inflating the buck is by way of conduit 50, valve casing 51 and conduit 52. In valve casing 51 are provided inlet valve 51a and outlet valve 51b mounted on a common stem 51c which is spring pressed to the position shown in Fig. 1 so as to maintain the inlet valve normally closed and the outlet valve normally open. The exhaust from the valve casing is by way of open port 51e. The valves in casing 51 are operated automatically in buck inflating direction upon engagement of latch 35. The arrangement shown comprises a lug 53 upon the operating lever 15 which engages the short arm 54 of valve operating lever 55 which is pivotally supported at 56 on a bracket connected with the frame. The longer arm 57 of this lever is held by a stop member 58 in position contacting stem 51c. As the latch 35 engages pin 38, lug 53 rotates lever 55 in a clockwise direction about its pivot so as to close valve 51b and open valve 51a to inflate the buck. The arrangement of lever 55 as shown provides a motion increasing mechanism between operating lever 15 and valve stem 51c so that a slight movement of lug 53 causes a greater movement of arm 57 of lever 55 so as

to cause satisfactory valve operation with slight movement of the operating lever.

With the parts in the position of Fig. 1, the operation of the pressing machine is as follows: Having arranged the lay of the work upon the 5 pressing surface of buck 14, the operator depresses the manuals 29d and 30d. It will be obvious that both manuals must be depressed, as the release of either of them will open one of the outlet valves and prevent the building up of 10 operating pressure in motor 24. It is necessary to maintain both manuals in operated position until the press is closed and latched as otherwise the flow of pressure fluid to motor 24 will be interrupted and spring 13 will return the chest 15 to open position. When the press parts reach closed position, pin 38 engages notch 37 in the latch 35 and thereafter the operator may release the two-hand control manuals. Upon engagement of latch 35, lug 53 on the operating lever 20 actuates the valve operating lever 55 in a clockwise direction which moves the valves in casing 51 to the position of Fig. 2 which inflates the buck so as to distend cover 45 into pressing engagement with the chest. Upon completion of 25 the pressing operation treadle 40 is depressed which disengages the latch and permits spring 13 to open the press which will move the operating lever in a counterclockwise direction. Upon a very slight movement of this operating lever 30 15, lever 55 moves sufficiently in a counterclockwise direction to permit the spring in valve casing 51 to return the valves to the position of Fig. 1, thus deflating the buck cover and preventing injury thereto. 35

I have thus provided a press which is safer than other presses known to me because it is more positive in its action. Where toggle mechanisms are relied on to lock a press in closed position, the working parts become worn so that 40 there is no fixed relation between the position of the press parts and the application of final pressure thereto. In my improved press the latch must be positively engaged before final pressure is applied and with the parts arranged as shown 45 there is little chance for ordinary wear to disturb the original relationship between latch engaging and final pressure producing parts. Furthermore, the two-hand control for closing the press insures that both hands of the operator are beyond 50 risk of injury until the press is latched closed.

For simplicity of language the term "closed" and similar expressions are used in the specification and claims to indicate a position in which 55 the press members are opposed and either in contact or sufficiently close to cause ironing contact between opposed pressing surfaces when the inflatable member is distended.

What I claim is:

1. In a press of the class described, a frame, a head lever pivoted thereon, a head carried by said lever, a buck mounted on said frame and having a fluid distensible pressing face, power means, motion transmitting means between said power 65 means and head lever for closing the press, means having an operative connection with said motion transmitting means for latching said press closed, fluid means for distending the distensible face of said buck, a control valve therefor, and motion 70 increasing means having an operative connection between its point of greater motion and said valve and having another connection between its point of lesser motion and the motion transmitting means, the parts being so arranged that 75

movement of the motion transmitting means to cause engagement of the latching means serves to open said valve.

2. In a press of the class described, a frame, a head lever pivoted thereon, a head carried by said lever, a buck mounted on said frame and having a fluid distensible pressing face, an operating lever, operative mechanism between said operating lever and said head lever, means for moving said operating lever in press-closing direction, coacting latch means on said frame and said operating lever for holding said press closed, fluid means for distending the distensible face of said buck, a control valve therefor, a valve actuating lever of the first order having a long and a short arm, said long arm having an operative connection for opening said valve, and said operating lever having a portion adapted to move the short arm of said valve actuating lever in valve-opening direction upon engagement of said latch means.

3. A pressing element comprising a base member having a work-supporting portion and depending side portions, a flexible distensible fluid-tight cover extending across said base member and downwardly along the side portions thereof, means securing said cover at its free edges to said base member in fluid-tight relation, and a supporting member secured to said base member and extending upwardly outside said cover along the side portions of said base member and sub-

stantially to the plane of said work-supporting portion.

4. A pressing element comprising a base member having a work-supporting portion and depending side portions, a flexible distensible fluid-tight cover extending across said base member and downwardly along the side portions thereof and then beneath said base member, a rigid flanged member having a portion clampingly securing the free edges of said cover to the under side of said base member, and said flanged member having another portion extending upwardly outside said cover along the side portions of said base member and substantially to the plane of said work-supporting portion.

5. A pressing element comprising a base member having a central portion and side portions extending at an angle thereto, a flexible distensible fluid-tight cover extending across said central portion and along said side portions and then turned inwardly at its free edges, means securing the free edges of said cover to said base member in a fluid-tight manner, and a plate member extending outside said cover along said side portions substantially to the plane of said central portion to support those unsecured portions of said cover outside the pressing zone when the central portion of said cover engages a coacting surface during a pressing operation.
